UNITED STATES PATENT OFFICE.

CHARLES F. THOMAS, OF WILMINGTON, DELAWARE.

IMPROVEMENT IN INDEXES.

Specification forming part of Letters Patent No. 154,299, dated August 18, 1874; application filed December 6, 1873.

To all whom it may concern:

Be it known that I, CHARLES F. THOMAS, of Wilmington, in the county of New Castle and State of Delaware, have invented a new and valuable Improvement in Indexes; and I do hereby declare that the following is a full, clear, and exact description of the construction and operation of the same, reference being had to the annexed drawings making a part of this specification, and to the letters and figures of reference marked thereon.

The figure of the drawing is a representation of my index.

This invention has reference to indexing ledgers and other books for keeping records and accounts; and it consists in a novel arrangement and combination of alphabetical letters with squares, which are marked off on the sheets, whereby a correct and ready index of names can be made by simply observing the initial letters of the surnames and Christian names, and referring to the number of the page registered in the square corresponding to such names.

The following is a description of my improved index.

In the annexed drawing, the alphabet, which is arranged on the extreme right-hand edges of the leaves, and which corresponds to the number of leaves in the index, represents the initial letters of surnames, which are referred to by turning the leaves in the usual well-known manner. Opposite each letter of this alphabet is a letter corresponding thereto. These letters are printed on each page of the index in alphabetical order, commencing with the letter A near the top of each page, and terminating with the letter Z at the bottom of the page. This alphabet represents Christian names.

Across the tops of the two pages, and inclosed in a bar above the alphabet last described, is another alphabet, preferably arranged to read from right to left, which designates the middle names of persons.

The pages are marked off in right-angular squares, running from side to side of the pages, and from top to bottom thereof, which squares correspond to the letters of the three alphabets above described.

If desirable, prominent lines, properly spaced, and extending from the tops to the bottoms of the pages, may be adopted, which lines, if more prominent than the other lines forming the squares above referred to, will quickly

guide the eye to the initial letter which it is desired to find in the middle-name alphabet.

I may also, if desired, print a duplicate middle-letter alphabet at the bottoms of the pages, and a Christian-name alphabet at the left-hand edges thereof, corresponding, respectively, to the alphabets at the tops and right-hand edges of the pages.

Suppose an account is to be opened with John Doe: The initial letter, D, is found in the surname-alphabet, which gives the page in the index for this name. The finger is then run down the Christian-name alphabet to the letter J, opposite which is found the square in which should be marked the number of the page in the ledger on which the said account is made.

If a person should have a middle name—as, for instance, H. W. Roe—the initial letters of the surname and Christian name are found as before described; and the middle name, W., is found by following the horizontal row of squares corresponding to H, the initial letter of the Christian name, to the square which corresponds to the W row of the middle-name alphabet, in which square the proper number of the page on which the account is to be opened in the ledger is registered.

If two similar names occur, any figure, letter, or other character fixed upon may be adopted which will properly distinguish these duplicate names. A similar plan may be adopted for duplicate initials.

It will be seen from the above description that I index the pages only, and thus do away entirely with writing names in the index. I thus save time, labor, and material.

What I claim as new, and desire to secure by Letters Patent, is—

The index, consisting of the pages laid off in squares by horizontal and vertical lines, clipped for the usual marginal surname-initial alphabet, and having the middle-name and Christian-name initial alphabet arranged at right angles with each other along the adjacent edges of each page, as specified, all being combined as described.

In testimony that I claim the above I have hereunto subscribed my name in the presence of two witnesses.

CHARLES F. THOMAS.
